UNITED STATES PATENT OFFICE.

AUGUST MAYKE AND FRITZ LANGHEINRICH, OF COTTBUS, GERMANY,
ASSIGNORS TO THE BREMER LINOLEUMWERKE DELMENHORST, OF
DELMENHORST, GERMANY.

PROCESS OF PRODUCING MATERIAL FOR COVERING FLOORS.

SPECIFICATION forming part of Letters Patent No. 644,827, dated March 6, 1900.

Application filed December 5, 1899. Serial No. 739,302. (No specimens.)

To all whom it may concern.

Be it known that we, AUGUST MAYKE and FRITZ LANGHEINRICH, subjects of the King of Prussia, German Emperor, residing at Cottbus, in the Kingdom of Prussia, Germany, have invented certain new and useful Improvements in and Connected with Processes for the Production of a Material for Covering Floors and for other Purposes, of which the following is a specification.

It is well known to produce floor-coverings or floor-cloth (the so-called "linoleum") from wood-dust instead of from cork, which material has been principally employed. The wood-dust is produced by grinding wood into a flour-like mass, and this is moistened by means of linseed-oil or any other kind of oil mixture or other binder. The mass thus obtained is spread over a textile material, whereupon the mass is dried and oxidized by exposing the same within drying-rooms to heat as well as to open air and also to light. The common wood-dust, however, presents the disadvantage that it is not suitable for absorbing the oil sufficiently. Therefore the oil does not get mixed with the wood-dust in an intimate and finely-distributed manner, and it forms a mixture of particles of wood and of oil which is not homogeneous and in which the oil must be present in a proportionately-large quantity in order to effect an active combination of the particles of wood with one another. Consequently the drying and oxidation of the mass—that is, the binding of the same—takes a very long time, so that the production of the floor-cloth is rendered exceedingly expensive. According to our present invention a material has been provided which is suitable for readily absorbing the oil and which will quickly mix with the oil in an extremely-fine distribution, while the oil, being in excess and therefore not sucked up by the material, does not remain within the mass, as it is not required for the combination of the wood particles with one another. Therefore the mass will dry and oxidize very much quicker than hitherto, so that the production of the floor-cloth will be accelerated and rendered inexpensive. In consequence of the

equally-fine distribution of the oil within the material the floor-cloth is made more elastic than the common cloth used up till now, and it will be seen that the elasticity of the floor-cloth proves to be a very valuable property of the same. The new material consists of wood-shreds made from wood-dust. This material may be produced by pressing the wood-dust into a mass, preferably in the form of blocks, which may be torn again by willowing-machines, so that a kind of wool is obtained consisting of the finest wood-shreds. The character of this material is entirely different from that of the wood-dust. While wood-dust consists of particles which are round, oval, square, &c., the said wood-shreds consist only of small felted hair-like portions. These hairs or fibers may be united into a compact mass by simply pressing the same by hand, which cannot be done with the common wood-dust.

The process is carried out in its details as stated in the following: Common wood-stuff, (wood-dust,) being in a moistened state, is impregnated with the color to be given to the floor-covering or floor-cloth, whereupon the so-colored wood-stuff is pressed into blocks of any suitable size or shape by means of any suitable pressing arrangements. The blocks after having been dried are torn or willowed to shreds. This may be done by means of willowing-machines of the kind used in cloth manufacture for willowing wool, or rollers of sheet-steel may be employed, which are cut or roughened in the manner of fine graters and which also tear or pluck the blocks into shreds. The finer the shreds are plucked the more valuable and beautiful the appearance of the floor-cloth will be. If this material obtained in the aforescribed manner is impregnated with oil or other binders, each single shred absorbs only so much oil until it is entirely impregnated. Therefore the mass contains only the oil sucked up by the shreds in a fine distribution, but the mass does not contain any oil in excess. When for this reason the mass is exposed to the open air to light and heat, the oxidation of the oil, and consequently the binding of the

mass, takes place more rapidly than hitherto. Now the mass is spread over textile materials and is united with the latter by means of heat and pressure, so that a compact and elastic 5 floor-cloth is formed, which will be ready for use within eight days. According to our invention the production of the floor-cloth requires at the most five weeks' time.

It appears to be preferable to employ for 10 our process as a binder linseed-oil which has been prepared by boiling with litharge, wax, soda, or caoutchouc.

Instead of dyeing the wood-dust before 15 pressing the same into blocks, in order to obtain the required color of the floor-cloth, the dyeing may be done on the material which is obtained after the blocks have been torn or willowed. The latter would be more advantageous, as the shreds easily suck up the dyeing liquid and are equally impregnated by 20 the same. In this case a repeated drying of the shreds is necessary before the same are impregnated with the oil, as the shreds would not suck up the oil in a wet state. This special drying, which renders the production of 25 the floor-cloth rather expensive, is dispensed with if the coloring is done on the wood-dust, as the latter must be moistened anyhow before being pressed into blocks.

The floor-cloth produced according to our 30 process may be made with any desired coloration or designs. The color cannot be worn out, as the mass is equally colored throughout. Besides, the coloring is obtained in the most easy and simple manner.

Instead of employing the material produced according to our process as floor-cloth it may 35 also be used for various other purposes. Instead of ordinary wood-shreds other ligneous materials could be used also.

Having now described our invention, what 40 we claim as new, and desire to secure by Letters Patent, is—

The process herein described of producing 45 material for floor-cloth or the like consisting in pressing wood-dust or other ligneous material into a mass, willowing said mass to produce shredded material and then mixing said willowed shreds with oil or a binding material, substantially as described.

In witness whereof we have hereunto set our hands in presence of two witnesses.

AUGUST MAYKE.
FRITZ LANGHEINRICH.
